UNITED STATES PATENT OFFICE.

EDWARD A. BIECHELE, OF CANTON, OHIO.

FURNACE.

1,025,673.

Specification of Letters Patent.

Patented May 7, 1912.

Application filed December 12, 1910. Serial No. 596,885.

To all whom it may concern:

Be it known that I, EDWARD A. BIECHELE, a citizen of the United States, resident of Canton, county of Stark, and State of Ohio, have invented a new and useful Improvement in Furnaces, of which the following is a specification, the principle of the invention being herein explained and the best mode in which I have contemplated applying that principle, so as to distinguish it from other inventions.

My invention relates to hot air furnaces, its object being to provide a furnace construction which will be simple in its construction and economical in its operation.

A specific object of the invention is to utilize to as great a degree as is possible the heat contained in the gases of combustion for heating the air.

20 The said invention consists of means hereinafter fully described and particularly set forth in the claims.

The annexed drawings and the following description set forth in detail certain means 25 embodying the invention, the disclosed means, however, constituting but one of various mechanical forms in which the principle of the invention may be used.

In said annexed drawing, the figure represents 30 a vertical axial section of a furnace embodying my invention.

As illustrated, the furnace is provided with the usual outer shell A, in the interior of which is placed the combustion chamber B having the feed inlet C, and the usual grate construction D, together with the ash-pit E and usual cleaning door e therefor. The combustion chamber B is removed some distance from the outer shell A, so as to form 40 the interior air-space F which surrounds the sides and top of said combustion chamber. The upper portion of the air-space is provided with the uprights f f to which the hot air pipes are connected.

45 Extending through an opening a in the side of the shell A is an air-duct G, which consists of the main duct portion G' and a casting connection G², which connects the part G' with the upper part of the air-space F. This connection is provided with a cylindrical portion G³ and a plurality of upright elbows g g. These elbows extend 50 through suitable openings b formed in the top of the combustion chamber. The horizontal portion G³ of the connection consists of an outer portion g' and an inner portion

g². The outer portion g' is fitted in an opening b' formed in the side of the combustion chamber, and the inner portion g² forms the horizontal portion of the outlet duct or smoke-pipe, for conducting away the gases of combustion. This duct g² communicates at g³ with the interior of the combustion chamber, the inlet openings so formed being therefore located intermediately of the branches g and communicating with the spaces b² between the upright portion of said branches. The outer end of the portion G' of the cold air duct is closed by means of a plate g⁴. The opening g⁵ forms the inlet for the cold air duct, whereby communication between the interior of same and the atmosphere is established. The lower portion of the air space F communicates with the atmosphere through an opening f', adjacent which may be secured a cold air inlet duct A'.

In operation, the gases of combustion surround the portion G² of the cold air inlet which is located in the interior of the combustion chamber, as previously described, and thoroughly heats same. These gases rise and pass through the openings b² between the upright branches g, thence downwardly through the opening g³, and out 85 through the outlet duct g² into the atmosphere. At the same time, the air in the space F is heated by its contact with the shell of the combustion chamber, and by radiation of heat therefrom. This heated air 90 rising, causes the influx of air through the openings f' and g⁵. The air passing through the latter opening comes into contact with the smoke pipe g², and is heated by contact and radiation therefrom. This latter heated 95 air passes upwardly through the branches g and into the upper portion of the air-space F. A constant circulation of air is therefore had in the cold air inlet G, and in the connection G², together with its branches g. 100 This constant circulation prevents the burning of the casting G² in the interior of the combustion chamber, and the structure formed as above described at the same time presents a maximum heating surface to said 105 gases of combustion while being formed in the combustion chamber, and also while being drawn upwardly through the smoke-pipe.

It will be readily understood that the portion G' of the air inlet may be extended outwardly to any desired distance consistent 110

with economy of construction, the greater such distance the longer will the cold air be in contact with the smoke pipe, and the more heat drawn therefrom to such air.

5 In the above described manner, I obtain a furnace simple in its construction, and having a high degree of economy in so far as relates to the abstraction of the maximum amount of heat evolved in the combustion 10 chamber and transmitted to the cold air drawn from the exterior.

Having fully described my invention, what I claim and desire to secure by Letters Patent is:—

15 1. In a furnace, the combination of a combustion chamber; an outer casing surrounding said combustion chamber and forming an air-space; a cold-air duct-member traversing said combustion chamber, discharging 20 into said air-space and having its inlet end in communication with the atmosphere; and an outlet-duct having its inner end communicating with the interior of said combustion chamber, surrounded by said cold- 25 air duct-member, of smaller diameter than the latter, so as to form an intervening air-

space and passing through the inlet-end of the latter.

2. In a furnace, the combination of a combustion chamber having a side opening and a plurality of top openings; a cold-air duct-member fitted in said side opening and provided with a plurality of integral branches fitted in said top openings and with an interior outlet duct having its inner end communicating with the interior of the combustion chamber and passing outwardly through the inlet-end of the cold-air duct-member; said outlet-duct being formed integrally with the latter and of smaller diameter than 30 same, so as to form an intervening air-space; an outer casing surrounding said combustion chamber; and a second duct-member connecting the inlet-end of said first-named duct-member with the atmosphere and passing 35 through said casing.

Signed by me, this 10th day of December, 1910.

EDWARD A. BIECHELE.
